Primary Examiner — Elizabeth J Oswecki(74) *Attorney, Agent, or Firm* — QuickPatents, LLC; Kevin Prince(57) **CLAIM**

The ornamental design for a cleat with kicking zones, as shown and described.

DESCRIPTION

FIG. 1 is a perspective view of a cleat with kicking zones, showing my new design;

FIG. 2 is a top plan view thereof;

FIG. 3 is a left-side elevational view thereof;

FIG. 4 is a front elevational view thereof;

FIG. 5 is a rear elevational view thereof;

FIG. 6 is a right-side elevational view thereof; and,

FIG. 7 is a bottom plan view thereof.

The broken lines showing shoe laces in FIGS. 1-4 and 6 and oblong areas in FIG. 7 depict environmental matter and form no part of the claimed design. A cleat for the left foot is illustrated, it being understood that the design for a cleat for the right foot is a mirror image thereof.
